[57] **CLAIM**

The ornamental design for a toy shed, as shown and described.

DESCRIPTION

FIG. 1 is a top perspective view of a toy shed showing my new design;

FIG. 2 is a rear elevational view thereof, shown on a reduced scale;

FIG. 3 is a left elevational view thereof; and,

FIG. 4 is a top plan view thereof.

The unshown bottom of the design is substantially flat, plain and unornamented.

FIG. 1

FIG. 2

FIG. 3

FIG. 4
